UNITED STATES PATENT OFFICE.

LOUIS WILPUTTE, OF NEW ROCHELLE, NEW YORK, ASSIGNOR, BY DIRECT AND MESNE ASSIGNMENTS, TO WILPUTTE COKE OVEN CORPORATION, OF NEW YORK, N. Y., A CORPORATION OF MAINE.

COKING PROCESS AND APPARATUS THEREFOR.

Application filed July 6, 1922. Serial No. 573,181.

In the manufacture of by-product coke it is sometimes desirable to supply steam or other fluid to the coking chambers during the final stages of the coking operations carried on in said chambers and the general object of my present invention is to provide an improved method of, and improved means for introducing fluid into a coking charge especially adapted for use where the coking operation is carried out in coking chambers of the type now generally employed in the manufacture of by-product coke.

The various features of novelty which characterize my invention are pointed out with particularity in the claims annexed to and forming a part of this specification. For a better understanding of my invention, however, and its advantages, reference should be had to the accompanying drawings and descriptive matter in which I have illustrated and described preferred embodiments of my invention.

Of the drawings:

Fig. 1 is a longitudinal sectional elevation of a coking chamber;

Fig. 2 is a partial sectional elevation taken through one of the coking chamber doors;

Fig. 3 is a view taken similarly to Fig. 2; and

Fig. 4 is an end elevation of a portion of the coke oven structure shown in Fig. 1.

In the drawings, A represents a coking chamber in a coke oven battery of a type in general use throughout the world in the manufacture of by-product coke. In present day practice in this country, each such coking chamber is from 10 to 12 feet high, is in the neighborhood of 40 feet long, and is of average width of from 14 to 21 inches. The top, bottom and side walls of each retort are made of masonry and form rigid permanent portions of the oven battery. The ends of the retort are closed by removable doors B each of which comprises an outer metallic frame and an inner portion, or lining B' of fire brick. Normally closed openings A' are provided in the top of the oven structure through which the coal is passed into the oven chamber in charging the latter. Each chamber A is also provided with one or more outlets A² for the gases generated in the chamber, these outlets being connected

to a suitable piping system (not shown). The side walls of each retort are provided with flue spaces for the heating gases by which the requisite heat is supplied for carbonizing the coal.

For the introduction of steam or other fluid into the charge C in each retort I form channels C' in the charge. These channels preferably extend into the charge in directions parallel to the length of the retort, and approximately midway between the side walls of the retort. Each channel made extends into the charge from one end nearly to the other end of the charge, or as shown, may be arranged in aligned pairs extending into the charge C at its opposite ends each nearly to the center of the charge. The channels C' may be provided at different levels, but in general I consider it sufficient to provide a single channel, or pair of aligned channels C' located in the lower portion of the charge and preferably at a distance from the bottom wall of the charge approximately as great as, or a trifle greater than, half the width of the retort.

I form these channels by means of cores D which may be iron or steel pipes two inches or so in diameter. These cores may be put in place at the time the retort is charged, or they may be inserted after the retort is charged at any time prior to the time at which the central portion of the charge begins to harden under the heat to which it is subjected. Each core D is withdrawn after the portion of the charge around the core has hardened or set, and before this portion of the charge has heated up to a temperature injurious to the metallic core. Each core D is withdrawn through a corresponding opening B³ formed in the corresponding door B. Preferably the openings B³ are substantially larger in diameter than the cores D so that any settlement of the charge with the cores in place will not interfere with the ready removal of the cores. When, as I consider preferable, the cores are put in place after the retort is charged I make the inner end of each core D pointed as indicated at D' to facilitate the forcing of the core into the charge. At its outer end each core may be provided with an internal shoulder D² or other provisions for engagement by a suit-

able core extracting means. In practice I maintain a core inserting and retracting mechanism on the coke discharging machine or "pusher" or otherwise providing suitable mechanism at one or both sides of the oven structure for inserting and removing the cores D, but I have not thought it necessary to illustrate or describe such mechanism herein.

10 Suitable provisions are required for sealing the apertures B³ to prevent the admission of air to the chamber A, through these apertures, or the escape therethrough of gases generated in the chambers. These provisions may obviously be constructed in various ways. In the simple and effective form shown, the closure means for the passages B³ comprise a conical plug E which may be formed of metal and when in place fits 20 against a tapered seat B⁴ provided at the outer end of the door aperture B³. Means shown for holding each plug E in place comprise a sliding part F having a wedge face engaging the outer end of the plug and 25 comprising a stem portion F' slidably received in keepers or guides B⁵ carried by the metallic framework of the door.

After the walls of the channels C' have set or hardened, and the cores D have been 30 withdrawn, steam or other fluid is discharged into the outer end of each channel as and when desired. The particular form of steam supplying means shown by way of example comprise nozzle pipes G carried by plugs EA which may be identical in construction with the plugs E except that the plugs EA are formed with thoroughfares E' into the inner ends of which the pipes G are secured. The pipes G preferably extend beyond the inner faces of the doors and into the channels C' for a few 40 inches. Any suitable external provisions may be made for supplying fluid at the proper time to the nozzle pipes G. As 45 shown the outer ends of the thoroughfares E' are connected by flexible steam hose sections H and valves H' to suitably disposed fluid supply pipes I. To facilitate the insertion and removal of the plugs E and EA provisions may be made for releasably holding each sliding member F up out of its normal positions. The provisions illustrated for this purpose comprise a chain H secured to each door above the sliding part 50 F and provided at its free end with a hook H', adapted to enter an aperture F² formed for the purpose in the upper end of the stem F' of the corresponding member F.

The invention is especially adapted and 60 intended for use where it is desirable to increase the gas yield of coke ovens by adding to the distillation gases properly produced, a certain amount of water gas. For accomplishing this result in accordance with 65 the present invention, steam is blown into

each of the channels C' for a greater or less period of time after the coking operation is wholly or largely completed. For example, in one contemplated use of the invention, I contemplate supplying steam to the 70 channels for a period of three or four hours at the end of or during the final portion of the coking operation, and to supply the steam at such rate as to convert one or two percent or so of the carbon in the charge 75 into the carbon monoxide constituent of water gas. It will be understood, however, that the invention may be employed to form either a greater or less amount of water gas than that mentioned. 80

I am aware that it has heretofore been proposed to pass steam into the coking chamber of by-product coke ovens in order to supplement the gases of distillation by water gas, but I believe I am the first to introduce 85 the steam in such retorts through channels formed in the body of the charge as distinguished from introducing it into the chamber at the outer surface of the charge through channels formed in the brick-work walls of 90 the retort. By passing the steam into supply connections passing through or carried by the oven doors, I not only bring about a more advantageous contact of the steam with 95 the charge, but I also avoid exposing the stationary highly heated fire brick walls of the oven structure to the cooling action of the gas supplied, and avoid all danger of having the steam supply passages clogged 100 with coal or coke in the oven charging and discharging operations. By proceeding in accordance with the present invention the supply connections in their entirety are readily accessible, and can easily be renewed 105 or repaired when this is desirable.

The invention is obviously useful in introducing other fluids than steam into the coking chambers to act on the charges therein. For example, the invention may be 110 used to supplement the coal distillation gases by oil gas. For this purpose oil in liquid or gaseous form is injected into the channels C through the nozzles G or analogous devices.

While in accordance with the provisions of the statutes I have illustrated and described the best form of my invention now known to me, it will be apparent to those skilled in the art that various formal changes may be made without departing from the spirit of 115 my invention as set forth in the appended claims, and that certain features of my invention may sometimes be used to advantage without a corresponding use of other features. 120

Having now described my invention, what I claim as new and desire to secure by Letters Patent is:

1. In coking carbonaceous material in a by-product coke oven, the improvement 130

which consists in forming a channel in the charge being coked during an initial stage of the coking operation, and injecting into said channel during the final stage of the 5 coking operation a fluid interacting with the hot coke mass to produce a combustible gas.

2. In coking carbonaceous material in a by-product coke oven, the improvement which consists in forming a channel in the 10 charge being coked during an initial stage of the coking operation, and injecting steam into the channel during a final stage of the coking operation.

3. In coking carbonaceous material in a 15 by-product coking oven having a coking chamber and a removable end door therefor, the improvement which consists in imbedding a channel forming core in a coal charge in said chamber in position to be axially 20 withdrawn from the charge through an aperture formed in said door, and spaced away from all walls of the coking chamber except the door, withdrawing said core through said aperture after the coking operation has 25 proceeded far enough to set the wall of the channel in the charge thereby formed, and subsequently injecting into said channel a

fluid interacting with the charge to form a combustible gas.

4. In a coke oven having a coking chamber 30 therein, the combination with a removable door closing one end of said coking chamber and having an aperture therein and a removable closure for said aperture, of provisions for sealing said aperture when said closure 35 is removed comprising a conical plug having a passage therein for a fluid and a fluid injecting nozzle connected to the inner end of said passage.

5. In a coke oven having a coking chamber 40 therein, the combination with a removable door closing one end of said coking chamber and having an aperture therein and a removable closure for said aperture, of means for moving said closure to permit the insertion 45 and withdrawal of a channel forming core bar through said aperture, and provisions for sealing said aperture including means for injecting a fluid through said aperture into said chamber. 50

Signed at New York, in the county of New York and State of New York this 5th day of July A. D. 1922.

LOUIS WILPUTTE.
